US0D1091251S

(12) **United States Design Patent** (10) **Patent No.:** **US D1,091,251 S**
(45) **Date of Patent:** **** Sep. 2, 2025**

(54) **WATER DISPENSER**

(71) Applicant: **ZHUHAI HENGQIN SUPER TECHNOLOGY LTD.**, Zhuhai (CN)

(72) Inventors: **Xueyuan Zhou**, Zhuhai (CN); **Tianle Yang**, Zhuhai (CN); **Yibao Zeng**, Zhuhai (CN)

(73) Assignee: **ZHUHAI HENGQIN SUPER TECHNOLOGY LTD.**, Zhuhai (CN)

(**) Term: **15 Years**

(21) Appl. No.: **29/916,554**

(22) Filed: **Nov. 13, 2023**

(30) **Foreign Application Priority Data**

May 31, 2023 (CN) 202330329158.3

(51) **LOC (15) Cl.** **30-07**

(52) **U.S. Cl.**

USPC **D30/122**

(57) **CLAIM**

The ornamental design for a water dispenser, as shown and described.

DESCRIPTION

FIG. 1 is a front, top perspective view of a water dispenser showing our new design;

FIG. 2 is a rear, top Perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings illustrate the portions of the water dispenser which form no part of the claimed design. Exterior portions of the water dispenser with stippling are intended to have a frosted appearance.

1 Claim, 8 Drawing Sheets
